UNITED STATES PATENT OFFICE.

BENNO MARSTALLER, OF MUNICH, GERMANY.

BORDER-PIECE FOR TRAVELING-TRUNKS.

No. 909,630

Specification of Letters Patent.

Patented Jan. 12, 1909.

Application filed June 11, 1908. Serial No. 427,914.

To all whom it may concern:

Be it known that I, BENNO MARSTALLER, manufacturer, citizen of Germany, residing at Munich, Bavaria, Germany, have invented 6 certain new and useful Improvements in Border-Pieces for Traveling-Trunks; and I do hereby declare the following to be a full, clear, and exact description of the invention, such as will enable others skilled in the art 10 to which it appertains to make and use the same.

The present invention relates to metal border-pieces for traveling trunks or the like, which form in section two grooves with 15 high sides, inverted relative to each other and fitting the one into the other.

According to this invention, the grooved border-pieces are arranged on the closing edges of the trunk and lid in such a manner 20 that even in the case of manufactured trunks or of trunks made of material liable to shrink, a permanent and burglar-proof joint will be insured.

Reference being had to the accompanying 25 drawing, Figure 1 shows a trunk fitted with such border-pieces in section, Figs. 2 and 3 being sections of the border-pieces on a larger scale, of which Fig. 3 shows a slightly modified form of construction.

30 These border-pieces, which may be made of any suitable kind of sheet-metal, possess two opposed grooves with high sides, fitting into or engaging with each other. The upper piece *e* presents a convex face while the lower border-piece (*a*) is bent in the form of 35 two adjoining grooves, of which the lower groove, formed by depending flange *b* is adapted to receive and inclose the upper edge of the body of the trunk and the other *f* 40 to receive the edge of the lid. In this manner a rigid connection of the trunk body and lid is insured when the trunk is closed. Further, the fact that the comparatively long sides of the two grooves will always act as 45 springs, makes these border-pieces especially suitable for manufactured trunks, since the wood or other material of the trunk need not fit quite exactly into said grooves, but may be left somewhat thicker; in this manner 50 allowance can also be made for a possible shrinking of the wood.

The groove (*f*) with its high sides *h* and *i* also makes it impossible to insert a bar or

other tool between the body and lid of the trunk, whereby the trunk is made burglar- 55 proof.

The tightness of the joint can further be increased by lining the groove (*f*), or the lid-edge (*e*), or both, with some soft material, such as, for instance, velvet. 60

The sides (*b*) of the lower groove of the border piece (*a*) may also be let into the sides of the trunk so that no projecting parts are left, which latter are often the starting-point or cause of breakages and damage to 65 the trunk.

On the outer side (*b*) of the lower border-piece (*a*), a projection (*c*) may be arranged, upon which the rim (*d*) of the upper border-piece (Fig. 2) will rest when the lid is 70 closed, whereby an additional tightening of the joint is secured.

In order to attain a tight joint, the upper border-piece may also be provided on one or both sides with projections (*g*), (Fig. 3), 75 which, when the lid is closed down, will rest on the upper edges of the sides (*i*) and (*h*) of the lower border-piece. This projection (*g*) may be formed in any suitable manner. It will be obvious that the here described 80 border-pieces may be equally well applied to traveling-bags or other receptacles, and the term trunk is used in a generic sense to include such.

What I claim as my invention and desire 85 to secure by Letters Patent, is:

1. A border-piece for trunks and the like comprising a metal strip of substantially **H** cross-section arranged to embrace the upper edge of the trunk body in its lower cavity 9 and to receive the lower edge of the trunk lid in its upper cavity.

2. A border piece for trunks and the like comprising an integral metal strip of sub- 95 stantially **H** cross-section arranged to embrace the upper edge of the trunk body in its lower cavity and to receive the lower edge of the trunk lid in its upper cavity.

3. A border piece for trunks and the like comprising an integral metal strip of sub- 100 stantially **H** cross-section arranged to embrace the upper edge of the trunk body in its lower cavity, in combination with a metal strip of **U** cross section arranged to embrace the lower edge of the trunk lid and to rest 105 in the upper cavity of the first named strip.

4. A border piece for trunks and the like comprising an integral metal strip of substantially H cross-section arranged to embrace the upper edge of the trunk body in its lower cavity, in combination with a metal strip of U cross-section arranged to embrace the lower edge of the trunk lid and to rest in the upper cavity of the first named strip, and provided with a downwardly depending

guard to overlie the outer face of the first named strip.

In testimony whereof I hereunto affix my signature in the presence of two witnesses.

BENNO MARSTALLER.
